UNITED STATES PATENT OFFICE.

GEORGE W. DOVER, OF LONGMEADOW, RHODE ISLAND, ASSIGNOR OF ONE-HALF TO
JOHN MONTGOMERY, OF WOONSOCKET, RHODE ISLAND.

CURTAIN HOLDER.

Application filed July 14, 1924. Serial No. 725,895.

To all whom it may concern:

Be it known that I, GEORGE W. DOVER, a citizen of the United States, residing at Longmeadow, in the county of Kent and 5 State of Rhode Island, have invented certain new and useful Improvements in Curtain Holders, of which the following is a specification.

This invention relates to a curtain holder 10 of the type adapted for use in connection with lace curtains, portières, and the like, and is adapted to be held in either its extended position for engaging the curtain or folded into retracted position wherein it occupies but little space and is out of the way 15 of the occupants of the room.

One object of the invention is to provide a simple and efficient device of the character described which may be easily constructed 20 and readily operated for supporting curtains or like articles.

Another object of the invention is to provide a device of this character in which the supporting element is frictionally retained 25 in either its extended or retracted position, thus preventing its accidental displacement.

Other objects and advantages of the invention relate to certain improved details of construction and methods of operation as 30 will be more fully set forth in the detailed description to follow.

Referring to the drawings forming a part of this application and illustrating one embodiment of the invention:—

35 Fig. 1 is a fragmentary perspective view of a window casing illustrating the position of the parts of the holder structure when the same is in operative position for holding a lace curtain.

40 Fig. 2 is a side elevational view, partially in section, showing the location of the parts in two positions of the elongated curtain supporting member.

Fig. 3 is a vertical sectional view, taken 45 along the line 3—3 of Fig. 2, and,

Fig. 4 is a view similar to Fig. 3, showing a slightly modified construction.

Similar reference characters indicate corresponding parts throughout the several 50 views of the drawings, wherein 1 designates a window casing adjacent to which is supported a lace curtain 2 in the ordinary manner.

The curtain holder comprises a base member 3 preferably formed of sheet metal

which is secured to the casing 1 by any suitable or desired fastening devices such as screws 4 passed through openings 14 formed in the base member and threaded into the casing. A pair of arms 5 and 6 extend outwardly from the sheet metal base member 3 and are preferably formed integral therewith, the outer portions 7 and 8 of said arms being oppositely located relative to each other and bent to engage, throughout a certain portion of their extent, the opposite sides of an elongated curtain supporting member 9 a portion of which extends between and is pivotally supported by the arms. The opposed arms 5 and 6 are formed 60 of resilient material and the portions 7 and 8 thereof are adapted to frictionally engage the opposite sides of the curtain supporting member 9 to frictionally resist the movement of the elongated curtain supporting member about its point of pivotal connection with the arms. 65

In the present instance the elongated member 9 is pivotally supported by the portions 7 and 8 of the arms 5 and 6 by means 70 of small brads 10 and 11 forced inwardly through suitable openings formed in the portions 7 and 8 of the arms and into the elongated member 9, the brads 10 and 11 being arranged in substantial alignment with 75 each other. It is to be understood, however, that I may form a bore in the elongated member 9 and pass a small rod entirely through the member and through the aligned openings in the portions 7 and 8, or 80 any other suitable means may be employed for pivotally supporting the elongated member 9 from the portions 7 and 8 of the arms. In the form of the invention shown in Figs. 85 1 to 3, the portions 7 and 8 of the arms are provided with flat inner faces which frictionally engage opposite sides of the elongated member 9 by reason of the resilient character of the material from which the arms are formed whereby the movement 90 of the elongated member about its point of pivotal connection with the portions 7 and 8 of the arms is retarded, and as a further means for limiting movement of the elongated member about its pivot point a stop 100 12 is provided, which in the present instance is shown as formed by striking out a portion of the base member 3 and bending the same so that it extends in a direction substantially at right angles to the plane of the 105 110

base. The stop 12 is so located that it engages the upper surface of the elongated member rearwardly of the pivot point 13 when the elongated member occupies the 5 position shown in full lines in Fig. 2, to limit downward movement of the elongated member about its pivot point 13, and the end of the member 12 engages the side of the elongated member forwardly of its pivot 10 point 13 when the elongated member is turned into the position shown in dotted lines in Fig. 2, whereby the movement of the elongated member about its pivot point is limited and the elongated member when 15 turned into the position shown in dotted lines in Fig. 2 is held in that position by the stop 12 and the frictional engagement of the portions 7 and 8 therewith.

In the modified form of the invention 20 shown in Fig. 4 of the drawings, the outwardly extending portions 15 and 16 of the resilient arms 5 and 6 are curved transversely to fit about the opposite sides of the elongated member 9. In this construction the 25 heads 17 and 18 of the brads 10 and 11 are normally spaced slightly from the outer surfaces of the portions 15 and 16 of the resilient arms to permit the portions 15 and 16 of the arms to be forced outwardly as 30 the elongated member 9 is turned about its pivot. In this construction the stop 12 serves to limit the movement of the elongated member in either of two directions as 35 in the form shown in Figs. 1 to 3.

If desired, however, the stop 12 may be dispensed with in this form of the structure, and the elongated member held in horizontal position by the engagement of the 40 portions 15 and 16 of the resilient arms 5 and 6 with the sides of the member. Likewise the elongated member may be retained in its vertical position by the engagement of the portions 15 and 16 of the resilient arms therewith.

The structure herein described may be 45 used for various purposes other than that described above, such, for example, as supports for full length or short length lace curtains, in which event two holders will be used for each window, and the holders will be so positioned upon the window casing that the elongated members will swing in horizontal planes rather than in vertical planes as shown in the drawings.

When used as curtain supports the structure will be so applied to the window casing 50 that each elongated member 9 will extend inwardly in a horizontal direction across one-half of the width of the window to support one of the two curtains employed for covering the window, and each elongated member 9 will extend outwardly towards the interior of the room, thus swinging the curtain out of its normal position covering 55 the window, when the elongated member is

turned into the dotted line position shown in Fig. 2 of the drawings. In this use of the structure the elongated member 9 may be formed of metal tubing and may be so constructed in sections so that a part thereof will telescope within another whereby the same may be readily adapted for use in connection with windows of different widths. The use of the structure for supporting lace curtains involves practically 70 no structural changes over that illustrated herewith, as stated above, except that the structure is so applied to the casing that the elongated member moves in a horizontal rather than a vertical plane. 75

From the above it will be seen that I have provided a curtain holder capable of being readily formed and easily operated whereby the elongated curtain supporting member may be turned into horizontal curtain supporting position or vertical retracted position and held in either of these positions by means of the frictional engagement of the resilient arms therewith, to support a curtain or be withdrawn out of the way 80 of the occupants of the room.

Similarly, the structure may be readily employed for a variety of other purposes, such as supports for lace curtains which will permit the curtains being swung into their 85 normal position in front of the window or swung bodily inward towards the interior of the room whenever it is desired to remove the curtains temporarily from their normal position in front of and covering 90 the windows.

What I claim is:—

1. In a curtain holder, a base member, a pair of arms projecting outwardly from said base member, an elongated member pivotally supported by said arms, and a stop terminating short of the pivot point of said elongated member, whereby the side of said elongated member is engaged by the side of said stop in one position of said elongated member to limit the movement of said elongated member about its pivot point and the end of said stop is engaged by the side of said elongated member outwardly of its pivot point to limit movement of said elongated member in the opposite direction. 110

2. In a curtain holder, a base member provided with a pair of arms projecting therefrom, an elongated member pivotally supported by said arms, and a stop formed integral with said base member and terminating short of the pivot point of said elongated member whereby the side and end of said stop respectively engage one side of said elongated member on opposite sides of its pivot point to limit the movement of said elongated member in opposite directions. 120

3. In a curtain holder, a base member, a pair of arms integral with said base member and extending outwardly therefrom, an 125

- elongated member having one end thereof positioned between said arms and pivotally supported therefrom, and a stop for limiting the pivotal movement of said elongated member in either of two directions about its point of pivotal connection to said arms, said stop member being so positioned that one side thereof is engaged by that portion of said elongated member which extends inwardly from the pivot point in one position of said elongated member and serves as a stop therefor while the end of said stop member is engaged by that portion of said elongated member which extends outwardly from its pivot point in another position of said elongated member and serves to limit the movement of said elongated member about its pivot point in the opposite direction.
4. In a curtain holder, a base member, a pair of resilient opposed arms extending outwardly from said base member adapted to resiliently engage a member interposed therebetween, an elongated member having a portion thereof located between said resilient arms and pivotally supported thereby the portions of said resilient arms engaging said elongated member being shaped to fit closely against the sides of said elongated member to form a channel for said member whereby the elongated member is resiliently held against movement.
5. In a curtain holder, a base member, a pair of resilient opposed arms extending outwardly from said base member and shaped to fit the opposite sides of an elongated member interposed therebetween in one position of said elongated member, an elongated member having a portion thereof interposed between said resilient arms and pivotally supported thereby, whereby said elongated member is resiliently restrained from movement about its pivot point when in one position.
6. In a curtain holder, a supporting member of sheet metal shaped to form a base, a pair of resilient arms having portions arranged in substantial parallelism, and a stop,

all of said elements being of relatively thin flexible material, said arms and stop member being integral with said base; and an elongated member having a portion thereof located between said resilient arms and pivotally supported thereby in such position as to be engaged by said stop at points located on opposite sides of its point of pivotal connection with said arms in different positions of said elongated member.

7. In a curtain holder, a supporting member of sheet metal shaped to form a base, a pair of resilient arms having portions arranged in substantially parallelism, and a stop offset laterally from said arms, all of said elements being struck out from a sheet metal blank whereby they are integrally formed of relatively thin material; an elongated member having a portion thereof located between said resilient arms and pivotally supported thereby in position to be engaged by different portions of said offset stop at points on opposite sides of its point of pivotal connection with said arms in different positions of said elongated member to positively limit the movement of said elongated member in either of two directions.

8. In a curtain holder, a base member, a pair of resilient opposed arms extending outwardly from said base member shaped to fit the opposite sides of an elongated member interposed therebetween and form a channel for said elongated member whereby said member is resiliently held against movement in one position of the same, an elongated member having a portion thereof located between said resilient arms and pivotally supported thereby to resiliently limit the movement of said elongated member about its point of pivotal support, and additional means engageable by said elongated member for positively limiting its movement in one direction about its point of pivotal support.

In testimony whereof I have affixed my signature.

GEORGE W. DOVER.
